UNITED STATES PATENT OFFICE.

LUCIEN GRISSEL, OF LA CHAUX-DE-FONDS, SWITZERLAND.

WATCH-BALANCE TESTER.

SPECIFICATION forming part of Letters Patent No. 653,996, dated July 17, 1900.

Application filed June 12, 1899. Serial No. 720,256. (No model.)

To all whom it may concern:

Be it known that I, LUCIEN GRISSEL, a citizen of the Republic of Switzerland, and a resident of La Chaux-de-Fonds, canton of Neufchâtel, Switzerland, have invented certain new and useful Improvements in Machines for Testing Watch-Balances, of which the following is a specification.

The testing-machines built and used until now have a balance-wheel worked by any suitable mechanism to the number of vibrations wanted, above which the balance-wheel of the watch to be tested was made to oscillate, said balance-wheel being hung by its hair-spring to a suitable potency. That system, besides other inconveniences, had this very serious one that the way of suspension and pivoting of the hair-spring and balance-wheel not being the same when those parts were placed on the regulating-machine or in the movement it resulted very often in noticeable mistakes. That system, besides, required very great skill and close attention from the worker. The machine I have invented permits the testing of the balance-wheel and its hair-spring placed definitively on the cock of the movement, the difference in the vibrations being, besides, rendered more visible by means of hands indicating the fifths of a second, the seconds, and the minutes.

Figure I is a plan view of the testing-machine, and Fig. II a side elevation of it, showing on the machine the place where the cock bearing the balance-wheel to be regulated is placed. Fig. III is a bottom view of the parts shown in Fig. II.

Two similar barrels B B' communicate each their motion, by the medium of the wheels and pinions b b' A A' a a' C C' c c' L L' e e', to the escape-wheels E E', against which the lever-forks F F' are acting, a balance-wheel, G acting on the fork F'. The balance-wheel, as well as the escapement it is working, is so calculated as to give a determined number of vibrations, corresponding to the number of the balance-wheel's vibrations of the watch to be tested. The arbors of the pinions b and b' bear each a hand showing the number of minutes on the dials N N', respectively. The arbors of the pinions c c' are provided each with a hand S S', showing the seconds, and

the hands s s', attached to the pinions n n', which are acted upon by the wheels R R', show the fifths of a second. In order that 55 the two lever-forks F F' should act identically on each wheelwork and on each pair of hands, it is necessary that the balance-wheel and the hair-spring, which act upon lever F, be absolutely in identical working conditions as the 60 balance-wheel G.

An arm P, set on a sliding block d, may be moved, by means of an adjusting-screw V, into a sliding piece H, pivoting upon a milled head-screw h, screwed into a second sliding 65 block D, that may be moved into a slide J by a pinion k, acting upon a rack K, attached to the sliding block D, that pinion being worked by the knob M. The screw h is provided with a hole-jewel o, the hole of which corresponds to the pivot of the balance-wheel arbor to be tested. In the arm P a cylindric spindle p may be moved, opposite which is another spindle p', the threaded end of which is provided with a nut-screw y, allowing to 70 push down more or less that spindle, which is pushed up again by a spring r. A spring u acts also between the head U of the screw h and the piece H, so as to insure the contact of that piece with the sliding block D, while 75 giving a certain elasticity to that coupling arrangement.

To test a balance, the cock, with the balance-wheel on its arbor and the hair-spring, is placed between the two spindles pp', which 85 are regulated so as to obtain the suitable height insuring the desired contact of the balance-wheel roller with the fork of the lever F, the distance from the centers being obtained in moving in one direction or the other 90 the sliding block d, bearing the potency, by the screw V, and the sliding block D by the knob M, that sliding block bearing the screw h, of which the hole-jewel o constitutes the lowest point of the balance-wheel arbor pivoting, 95 the upper pivot pivoting naturally in its place in the cock. The balance-wheel being then in place and taken by the escapement and the two barrels wound up, the two balance-wheels are placed so that the seconds, minutes, and fifths-of-seconds hands are occupying the same position, then they are let start together between the two balance-wheels, the differences of vibrations being read on the 100

dials what allows to correct the distances between the two balance-wheels until they vibrate in unison.

Having thus described my invention, I
5 claim as new and desire to secure by Letters
Patent—

In a watch-balance-testing device having a frame or support carrying two trains of gearing and a testing-balance operated by one of
10 said gearing, a block D having a sliding connection with said frame adjacent to the other

train, a piece H pivotally connected with said block, an arm P having a clamp for holding the balance-bridge and balance to be tested, and a sliding connection between said arm 15 and piece H, substantially as described.

In witness whereof I have hereunto set my hand in presence of two witnesses.

LUCIEN GRISEL.
